CARBURETTOR VACUUM CONTROL DEVICE

Victor George Willmer, Toorbul, via Caboolture,
Queensland, Australia

Filed June 6, 1957, Ser. No. 664,011

Claims priority, application Australia June 8, 1956

2 Claims. (Cl. 192—3)

This invention relates to improvements in and relating to vacuum control devices for use with carburetors of vehicle internal combustion engines.

The operation of a carburetor of a car or motor cycle depends upon partial vacuum in the intake manifold which acts to draw the fuel from the carburetor jet. However, there is the disadvantage that when the engine is used as a brake or is otherwise over-run, a very considerable vacuum acts on the carburetor jet, with the result that an excess of incompletely atomised fuel is drawn into the engine cylinders, destroying the oil film thereon and causing crankcase dilution. Moreover, the over-rich fuel mixture results in the formation of carbon, with resultant low power output. As an automobile engine is very frequently over-run during normal operation, it will be apparent that there is a considerable wastage of fuel, as well as the deleterious effects mentioned.

Accordingly, my present invention has been devised to overcome these disadvantages, and it has for its principal object the provision of a device for attachment to or incorporation in the construction of a carburetor, and which is adapted to be brought into operation to eliminate or considerably reduce the vacuum exerted on the carburetor when the engine is being used as a brake or over-run.

Another object of the invention is to provide a device of the character described which may be used, if desired, to govern the driven speed of a vehicle without acting to reduce the efficiency of the vehicle at speeds up to a predetermined speed.

Further objects of the invention are to provide a device of the aforesaid nature which is relatively simple and inexpensive to manufacture and to install in a vehicle, and which will prove very efficient, trouble-free and durable in operation.

Other objects and advantages will be apparent from the following description.

In the drawings:

Figure 1 is a side elevational view of a device according to my invention, shown fitted to a car engine, part of which is indicated in broken outline;

Figure 2 is a half-sectional elevational view of part of the device shown in Figure 1; and

Figure 3 is a plan view along the line 3—3 of Figure 2, with certain parts omitted.

The vacuum control device shown in the drawings includes a hollow body 10 which is more or less T-shaped in plan view, an extension 11 of the body 10 being formed with registering apertures 12 at top and bottom. The said extension 11 is adapted to be fitted between the carburetor 13 and the intake manifold 14 of the vehicle engine, the apertures 12 communicating with the carburetor and intake manifold.

The main portion of the body 10 has formed through its upper face a round opening 15, the periphery of which forms a vacuum break valve seating 16 upon which there normally seats a vacuum break valve 17 which is

2

provided with a downwardly extending stem 18, vertically movable in a valve stem guide 19 formed in the lower part of the body 10.

Over the main portion of the body 10 there is removably fitted a cover 20 having a gauze-covered air inlet 21 at its front and an opening 22 at its top defined by an annular upstanding flange 23.

Mounted on the cover 20 centrally over the opening 22 thereof is an actuating-valve housing 24 formed as upper and lower portions 25 and 26 connected by screws and sealed from one another by an interposed valve diaphragm 27. To the bottom of the diaphragm 27 there is centrally secured an actuating rod 28 which passes down through a central aperture 28a in the base of the lower portion 26 of the housing 24, through the opening 22 of the cover 20, and through an oversize aperture (not shown) in one end of a lever arm 29, a washer 30 and split pin 31 being provided on the lower extremity of the actuating rod 28 beneath the said end of the lever arm 29. The other end of the lever arm 29 is pivoted in a bifurcated bracket 32 secured to the side of the cover 20, while an intermediate part of the lever arm 29 is pivotally connected to a pivot lug 33 extending up from the centre of the vacuum break valve 17.

25 A vacuum tube 34 is provided to connect the body 10 to the upper portion 25 of the actuating-valve housing 24, and this tube 34 has its ends secured in nipples 35 screwed into tapped apertures 36 and 37 in the body 10 and in the upper portion 25 of the actuating valve housing 24 respectively. Further tapped apertures 38 and 39 are provided in the top portion 25 of the actuating-valve housing 24 for the connection of control tubes leading to accelerator, clutch and dash-board connections.

The tapped aperture 39 has screwed therein a nipple 35 from which there leads a control tube 41 to a clutch-actuated air valve 42 mounted by means of a mounting bracket 43 on the side of the engine. This air valve is of a known type in which an air inlet 44 is normally maintained closed but may be opened when any degree 40 of inward movement is imparted to a spring-loaded stem or plunger 45 by means of a pivoted lever 46, the latter being connected in this case to an actuating rod 47 leading to the vehicle clutch (not shown) and adapted to be moved in the direction indicated by the arrow 48 whenever the clutch pedal is depressed. Thus the upper portion 25 of the housing 24 may be opened to atmosphere by way of the control tube 41 whenever the clutch pedal is depressed, but it will be closed to atmosphere in so far as the tube 41 is concerned whenever the clutch is

45 in normal released driving position, as will be the case when the engine is being used as a brake or over-run.

Within the tapped aperture 38 of the actuating-valve housing 24 there is screwed a T-shaped tube 49 of which one arm 50 is secured to an air inlet tube 51 of lesser 50 diameter. To the threaded outer end of the air inlet tube 51 there is secured by means of locknuts 52 one arm of a U-shaped spring steel valve member 53 the other arm of which passes the open end of the air inlet tube 51 and has a rubber pad 54 held in place by a metal plate

55. A central aperture (not shown) in the plate 55 allows the open end of the air inlet tube 51 to bear against the rubber pad 54 when the outer arm of the valve member 53 is moved towards the air inlet tube 51, and for this purpose, the said arm of the valve member 53 is connected by a tension spring 56 to a cable 57 extending to the dash-board indicated at 58 of the vehicle for operation by a control knob 59. Thus the air inlet tube 51 will normally vent to atmosphere the upper portion 25 of the valve housing 24, but it may be closed when desired by pulling the knob 59 to cause the valve member 53 to seal the end of the tube 51, the tension spring 56 acting to ensure that no undue strain will be placed on the valve

member 53 by forceful pulling of the knob 59 and cable 57.

The T-shaped tube 49 has its other arm 60 connected to one end of a control tube 61 leading to an externally-threaded connector tube 62 mounted on the engine by means of a mounting bracket 63. To the connector tube 62 is secured an air inlet tube 64 of lesser diameter provided with a valve member 65 similar in nature to and mounted in the same manner as the aforescribed valve member 53, the valve member 65 tending normally to maintain its sealing arm clear of the open end of the air inlet tube 64. However, this valve member 65 is arranged so that it will be held against the end of the air inlet tube 64 when the accelerator (not shown) of the vehicle is released or inoperative, and to be clear of the air inlet tube 64 only when the accelerator is pressed. To this end, an actuating rod 66 from the accelerator is pivotally connected to an arm 67 of a lever member which has another arm 68 connected by a pivoted throttle-operating rod 69 to the fuel-control mechanism (not shown) of the carburettor. A control screw 70 is mounted by means of a bracket 71 on the lever arm 67 so that when the accelerator is inoperative or released the screw 70 will bear against and urge the valve member 65 into closed position on the air inlet tube 64, but when the accelerator is pressed to move the rod 66 in the direction indicated by the arrow 72 the screw 70 will immediately move clear of the valve member 65 to cause the control tube 61 to vent to atmosphere the upper portion 25 of the valve housing 24.

In order that this opening of the air inlet tube 64 will take place before the fuel-control mechanism of the carburettor is operated by the rod 69, the latter has its upper end mounted slidably in a guide bracket 70a on the lower end of a rod's 71a leading to the fuel-control mechanism, the rod 69 being held normally by a compression spring 72 so that a nut 73 on its upper end will be spaced from a top plate 74 of the guide bracket 70a. When the rod 66 is moved upon depression of the accelerator, the valve member 65 will immediately move to open the air inlet tube 64, but the rod 69 will move a short distance against the action of the spring 72 before its upper nut 73 will strike the top plate 74 of the guide bracket 70a to cause the rod 71a to operate the fuel-control mechanism, the usual return spring (not shown) of the fuel-control mechanism being of greater tension than the spring 72 so that the above action will take place.

In the operation of the device, it will be apparent that the body 10 is subjected to vacuum within the carburettor and intake manifold, and it is required that the vacuum break valve 17 be raised when the engine is being used as a brake or over-run. As the vacuum tube 34 connects the body 10 to the upper portion 25 of the actuating-valve housing 24 above the valve diaphragm 27, it will be seen that the diaphragm will be raised by the carburettor vacuum if the apertures 38 and 39 are closed to atmosphere, so that the rod 28 will move the lever arm 29 to raise the valve 17 and break the vacuum in the carburettor and intake manifold. As previously described, the clutch-controlled valve 42 is normally closed when the clutch pedal is in released position so that the aperture 39 will be sealed to atmosphere when the engine is being used as a brake or over-run with the clutch pedal released. Similarly, the accelerator-controlled valve member 65 will be acting to close the air inlet tube 64 when the accelerator is in the released position of over-run, so that the aperture 38 will be closed to atmosphere as far as the tube 61 is concerned. Provided then the knob 59 of the cable 57 is pulled to close the valve member 53, the chamber within the upper portion 25 of the actuating-valve housing 24 will be closed to atmosphere and the diaphragm 27 will be moved to raised position as a result of the connection to the engine vacuum by the tube 34 so that the carburettor vacuum will be broken.

If at any time during over-run, it is desired to restore the carburettor vacuum, either the accelerator may be

pressed to open the valve 65, or the clutch pedal may be depressed to open the valve 42, or the knob 59 of the cable 57 may be released to open the valve 53. In any one of these cases, the chamber above the diaphragm 27 will be vented to atmosphere so that the vacuum through the tube 34 will lose its effect on the diaphragm 27 and allow the vacuum break valve 17 to return to closed position.

The device lends itself to the use of a governor device of any known type associated with the transmission of the vehicle or a wheel thereof, the governor being connected by a suitable cable to the valve member 65 so that when the vehicle reaches a predetermined speed the valve member 65 will be moved to close the air inlet tube 64 even though the accelerator will be pressed. As the clutch will be in released position at this stage, the diaphragm 27 will be moved to open the vacuum break valve 17 provided the knob 59 is in withdrawn position. Speed governing means of this character will be found to be very advantageous in that the performance of the vehicle engine below the predetermined maximum speed will not be impaired in any way.

While devices made and used in accordance with my invention will be found very effective in achieving the objects for which the invention has been devised, it will be understood that the particular exemplary embodiment of the invention hereinbefore described may be subject to many minor modifications of constructional detail and design which will be readily apparent to persons skilled in the art without departing from the scope and ambit of the invention as defined by the appended claims.

What I claim is:

1. In combination with an internal combustion engine having a carburettor, an intake manifold, and an accelerator control for the carburettor; a control device entirely vacuum-operated free of the speed of said engine for reducing the vacuum on the carburettor during periods of engine-braking or vehicle over-running, said control device including a chamber connected in communication with the carburettor and intake manifold, said chamber having an inlet for atmospheric air, a vacuum break valve normally closing such inlet, means responsive solely to vacuum conditions extant within said manifold for opening said valve to admit atmospheric air to the chamber to neutralize vacuum in the carburettor and intake manifold, a lost-motion connection in said accelerator control, and de-control means connected to said accelerator control for rendering said vacuum responsive means inoperative coincident with initial movement of said lost-motion connection, whereby the vacuum control device is rendered inoperative upon actuation of the accelerator control before regulation of the carburettor thereby.

2. In an internal combustion engine having a carburettor and an intake manifold, a control device entirely vacuum-operated free of the speed of said engine for reducing the vacuum on the carburettor during periods of engine-braking or vehicle over-running; said control device comprising a main chamber, a partition dividing said chamber into upper and lower sections and having an opening therein providing communication between the two such sections, said lower section being fitted between the carburettor and the intake manifold of the engine, said upper section having an inlet for atmospheric air, a vacuum break valve normally closing the opening of said partition, a movable vacuum responsive member operatively connected to said vacuum break valve and normally occupying a position with the valve closed, said movable member being mounted in a housing defining on one side of the member a vacuum chamber subjected to vacuum in the carburettor to draw the member into the vacuum chamber and thereby cause the valve to move to open position, at least one air inlet to such vacuum chamber provided with control means for opening and closing the same, opening of such inlet venting the vacuum chamber to the atmosphere to render said movable member inoper-

able and closure thereof sealing the vacuum chamber so that the member may be operated as aforesaid to control the valve in response to the vacuum within the carburetor, an accelerator control for said carburetor, said accelerator control including a lost-motion connection, and means operatively connecting the accelerator control to the control means in the air inlet to said vacuum chamber for opening such inlet coincident with the initial movement of such lost-motion connection, whereby the vacuum chamber is vented to the atmosphere before the 10 accelerator operates the carburetor.
